Primary Examiner — Kendra Leslie Hamilton(74) *Attorney, Agent, or Firm* — Kunzler Bean & Adamson, PC; Michael Bartholomew**CLAIM**

The ornamental design for a pet helmet with eye shield as shown and described.

DESCRIPTION

FIG. 1 is a front, left and top perspective view of a pet helmet with eye shield, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a rear, right and bottom perspective view of the pet helmet with eye shield of FIG. 2 in condition for use.

The dashed broken lines depict portions of the pet helmet with eye shield that form no part of the claimed design.
